CONVEYER STRUCTURE

Henry Sieb, Hammond, Ind.

Application September 20, 1944, Serial No. 554,897

4 Claims. (Cl. 198—168)

In my prior Patent No. 2,169,114 there is disclosed a machine for applying glue to the back edges of books that are still in the form of so-called sections that have been sewn together. Books are carried through the machine in groups wherein the books stand on edge and side by side. Each group of books is moved ahead by a rod or bar spanning the distance between a pair of endless chains and contacting the rear edges of the books. The books of each group are pressed together during the gluing operation so that the planes of division between them are not readily discernible, requiring considerable care on the part of the operator to separate the books in the same from each other.

The object of the present invention is to make it simple and easy to separate the books in each of the aforesaid groups after they have been glued.

A more specific object of the invention is to make it possible to carry out the main purpose thereof by means of a simple attachment to the machine of the aforesaid patent.

The various features of novelty whereby my invention is characterized will hereinafter be pointed out with particularity in the claims; but for a full understanding of my invention and of its various objects and advantages, reference may be had to the following detailed description taken in connection with the accompanying drawing, wherein:

Figure 1 is a transverse section through the upper part of the machine of the aforesaid patent, provided with the new attachments of the most highly developed form and showing in broken lines three books being carried through the machine; Fig. 2 is a section on line 2—2 of Fig. 1; Fig. 3 is a front view of one of the blocks or shoes and a fragment of the bar or rod on which it is mounted when in use in the machine; and Fig. 4 is a section on line 4—4 of Fig. 3.

In accordance with my invention I provide the transverse bars or rods of the machine with forwardly projecting parts, in spaced relation to each other; some of the books in each group registering with these parts and being driven ahead thereby, while the remainder are located between the projecting parts and are engaged by the bar as in the old machine. This causes some of the books in each group to be offset lengthwise with respect to the other books in that group; thereby giving to the group a toothed configuration at both the leading and the trailing ends, so that the operator can easily take hold of the ends of individual books instead of being required to hunt the planes of separation between the books.

Referring to the drawing, 1 is a horizontal bed or table on which the books to be glued rest, and 2, 2 are spaced parallel guides on top of and extending lengthwise of the bed or table. The guides are adjustable from and toward each other by a suitable mechanism including a shaft 3 extending underneath the bed from one side to the other; the shaft having thereon right and left hand threads 4 and 5 with which nuts 6, 6 are engaged. Each nut has a stem 7 that extends up through a transverse slot 8 in the bed or table below the corresponding guide, and through a foot flange on that guide. A nut 9 on the upper end of each stem serves to clamp the corresponding guide in any position into which it may be adjusted. Each guide contains a channel 10 that extends deeply into the same on the side facing the other guide. The upper runs of two endless chains 11, 11 run lengthwise of the guides within the channels; the chains being connected at intervals by cross bars or rods 12. All the parts just described are disclosed in my aforesaid patent and are believed to require no further explanation.

In the preferred form of my invention there are blocks or shoes 13 which can be secured in any desired positions along the bars or rods and be taken off, when desired, without disturbing the latter. The reason for this is that books are made in various thicknesses and each projection on the bars or rods should be just as long as the thickness of the book with which it is to engage. As many sets of blocks as there are thicknesses of books may be provided. Then, when books of a certain thickness are to be glued, the guides are set so as to provide room for the number of books that are to pass through the machine as a group, and then blocks or shoes of the proper length are secured upon each bar, the thickness of a book apart; thereby permitting a part of the books of each group to engage directly with the adjacent bar, as in said patent, while the remainder engage the blocks or shoes. The blocks are conveniently U-shaped, so that they may be slipped on the bars from the side and be then held in place by set screws 14 or the like. Also, the bars are preferably square or rectangular in cross section in order that the blocks will be prevented from turning about them.

After the machine has been properly adjusted and the blocks applied to the bars, the books may be fed into the machine in the usual way, the books in the paths of the blocks being engaged with the latter before the bar reaches the books in the spaces between the blocks. Consequently some of the books, shown in broken lines at A

in Figs. 1 and 2, are pushed a little ahead of the others in the same group. This displacement, to produce a toothed effect at the front and rear ends of each group of books, need not be more than about three eighths of an inch, so that the blocks may be small and light.

Sometimes, when special conditions are encountered, it is useful to have blocks that are adapted to be used with books of different thicknesses as, for example, when there are only three books in a group. It is such a block that I have illustrated in the drawing. The block proper may be as long as the thinnest book to be glued. Then, in lieu of additional blocks, one set for each different book thickness, I provide each of two of the short blocks with tongues 15 that project from one end flush with the front or working face of the block; these tongues being so located that they may project into the channels in the guides when the blocks are placed on a bar near the guides. In preparing the machine the guides are adjusted until they are spaced apart a distance equal to the thickness of three books. Then two of the blocks are put on each bar, each with its tongue entered in the channel in one of the guides. If the thickness of a book is equal to the length of the block proper, each block must be set close to the adjacent guide, and the space between the blocks will be a block length. However, for thicker books the tongues extend only part way into the channels and give the effect of longer blocks.

While I have illustrated and described with particularity only a single form of my invention, I do not desire to be limited to the specific structural details thus illustrated and described; but intend to cover all forms and arrangements that come within the definitions of my invention constituting the appended claims.

I claim:

1. The combination with a conveyer for books that has a bar extending across the rear ends of a group of books to move them ahead, of blocks detachably mounted on the bar in spaced relation to each other to engage some of the books while the remainder contact the bar in the spaces

between the blocks and thus cause the books to be displaced lengthwise of each other.

2. The combination with a book conveying apparatus in which there are parallel guides each having in the side facing toward the other a deep channel extending lengthwise thereof and a cross bar extending at its ends into the channels where they are attached to conveyers running in the channels, and in which the guides are adjustable from and toward each other, of two blocks adapted to be adjustably secured to the bar in spaced relation to each other, said blocks having faces to engage the rear edges of books between the guides and hold them at some distance from the bar, and each block having in the plane of the book-engaging face a tongue that extends into the adjacent channel, whereby of three books two will be driven by the blocks and be slightly in the lead of the third book in the space between the blocks and driven directly by the bar.

3. The combination with a conveyer for books that has a bar in position to extend across the rear ends of a group of books, placed side by side, to move them ahead, of blocks adapted to be attached to the bar in any one of a plurality of spaced relations to each other along the latter, whereby books engaged with blocks are displaced lengthwise of the direction of movement thereof by the conveyer relative to a book engaged directly with the bar, the width of a space between blocks being equal to the thickness of a book that is to enter it.

4. The combination with a book conveying apparatus that has a bar to extend across the rear of a group of books, placed side by side, to move them, and guides, adjustable from and toward each other, between which the books must pass, of two blocks adapted to be attached to the bar at any desired points along the latter, each block having a tongue projecting laterally in the plane of the book-engaging face, and the guides being constructed to permit the tongues on the blocks adjacent thereto to extend across the book-engaging faces of the guides.

HENRY SIEB.
